GAME APPARATUS

Hugh McKeever, Tulsa, Okla.

Application October 3, 1934, Serial No. 746,711

1 Claim. (Cl. 273—142)

The present invention relates to a new and improved game apparatus for use particularly in playing football in miniature, said apparatus being in the form of a rotary indicator or spinner 5 of the type including a housing or casing having windows therein and a rotary chance controlled dial or disk mounted in said housing or casing and having indicia thereon which is observed through the windows.

10 An important object of the present invention is to provide an indicator of the aforementioned character comprising a novel construction, combination and arrangement of parts through the medium of which the rotary disk or dial will be caused to stop at such positions that the indicia thereon will be in full view beneath the windows or openings.

20 Other objects of the invention are to provide an indicator or game apparatus of the character described which will be comparatively simple in construction, strong, durable, reliable in operation, compact, attractive in appearance and which may be manufactured at low cost.

25 All of the foregoing and still further objects and advantages of the invention will become apparent from a study of the following specification, taken in connection with the accompanying drawings wherein like characters of reference designate corresponding parts throughout the several 30 views, and wherein:—

Figure 1 is a view in top plan of the invention.

Figure 2 is a view in side elevation of the device.

35 Figure 3 is a fragmentary view in vertical section, taken substantially on the line 3—3 of Figure 1.

Figure 4 is a fragmentary view in horizontal section, taken substantially on the line 4—4 of Figure 3.

40 Figure 5 is a detail view in bottom plan of what will hereinafter be referred to as the turntable.

45 Referring now to the drawings in detail, it will be seen that the embodiment of the invention which has been illustrated comprises a casing 1 of suitable material and dimensions, the top 2 of which has formed therein a plurality of aligned windows or openings 3.

50 As illustrated to advantage in Figure 3 of the drawings, a base 4 of suitable material, such as wood, is mounted on the bottom 5 of the casing 1.

Mounted in the base 4 is a thrust bearing or socket 6 in which the enlarged lower end 7 of a spindle 8 is journaled. The spindle 8 extends rotatably through the top 2 of the casing 1 and has mounted on its upper end an operating knob or handle 9.

5 The base 4 has formed in its top depressions or sockets 10 in which balls 11 are rotatably mounted on shafts or rods 12. Fixed on the spindle 8 is a turntable 13 which rests on the shoulder which is provided on said spindle by the enlarged lower end portion 7 thereof. The turntable 13 rotates on the balls 11 and has formed in its lower side a circular series of indentations 14 in which said balls seat in a manner to cause the turntable 13 to stop only in predetermined positions. Also 15 mounted on the spindle 8 for rotation therewith and resting on the turntable 13 is a disk or dial 15 having suitable scoring or other indicia thereon which is observed through the windows or openings 3. As best seen in Figure 3 of the drawings, 20 the spindle 8 is provided with a threaded portion for receiving a nut 17 for securing the elements 13 and 15 to said spindle for rotation therewith. A cleat or washer 18 is interposed between the nut 17 and the dial 15. A bushing 19 is provided 25 between the spindle 8 and the top 2 of the casing 1.

30 It is believed that the manner of using the device will be readily apparent. The operator or player spins the dial 15 through the medium of the knob or handle 9 which, of course, also rotates the turntable 13. When the turntable comes to a stop the balls 11 enter a pair of the indentations 14 on opposite sides of the spindle 8 in a manner to cause the dial 15 to stop only in such positions that the indicia thereon will be in full view beneath the windows or openings 3.

35 It is believed that the many advantages of a game apparatus constructed in accordance with the present invention will be readily understood, 40 and although a preferred embodiment of the invention is as illustrated and described, it is to be understood that changes in the details of construction and in the combination and arrangement of parts may be resorted to which will fall 45 within the scope of the invention as claimed.

What is claimed is:—

50 A game apparatus of the class described comprising a casing including a top having a plurality of windows therein, a base fixed on the bottom of

the casing, said base having recesses in its top, a thrust bearing mounted vertically in the base, a spindle journaled in the thrust bearing and extending upwardly through the top of the casing, 5 said spindle including an enlarged lower end portion providing a shoulder and further including a threaded portion immediately above said shoulder, a turntable mounted on the spindle and engaged on the shoulder, a dial mounted on the spindle and resting on the turntable, a nut threaded on the spindle, a cleat interposed be-

tween the nut and the dial for securing the turntable and the dial to the spindle for rotation therewith, said dial having indicia thereon observable through the windows, an actuating knob on the upper end of the spindle, the turntable having indentations in its lower side, shafts mounted in the base and traversing the recesses in said base, and rotary balls mounted on the shafts and engageable in the indentations for bringing the dial to a stop in predetermined positions. 10

HUGH MCKEEVER.
